[57] CLAIM

The ornamental design for a package opening device for removing plastic wrapping, as shown and described.

DESCRIPTION

FIG. 1 is a top and side perspective view of a package opening device for removing plastic wrapping showing my new design;

FIG. 2 is a reduced front elevational view of the package opening device for removing plastic wrapping, the rear elevational view being a mirror-image;

FIG. 3 is a top plan view thereof;

FIG. 4 is a bottom plan view thereof; and,

FIG. 5 is a cross sectional view thereof taken along the line 5—5 of FIG. 3.
